UNITED STATES PATENT OFFICE.

FRANK H. LA PIERRE, OF EAST ORANGE, NEW JERSEY.

DESIGN FOR A BRACELET OR SIMILAR ARTICLE.

SPECIFICATION forming part of Design No. 28,720, dated May 31, 1898.

Application filed April 21, 1898. Serial No. 678,395. Term of patent 7 years.

To all whom it may concern:

Be it known that I, FRANK H. LA PIERRE, a citizen of the United States, residing at East Orange, in the county of Essex and State of New Jersey, have invented and produced a new and original Design for a Bracelet or Similar Article; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The single figure of the drawing is a perspective view of my newly-designed bracelet or similar article.

As shown in said drawing, the leading or material feature of my design consists in a bracelet having the shape of a golf-stick bent 20 into a ring and having its ends overlapping.

In said drawing, a indicates the body portion of the bracelet, having the shape of a golf-stick bent into a ring, and b is a ball-shaped ornament displayed at the outer overlapping ends of said body portion.

What I claim as new is—

The design for a bracelet or similar article as herein shown and described.

In testimony that I claim the foregoing I 30 have hereunto set my hand this 18th day of March, 1898.

FRANK H. LA PIERRE.
